UNITED STATES PATENT OFFICE

2,038,753

KNITTING MACHINE FOR THE MANUFACTURE OF TUBULAR YARNS

Wilhelm Neininger, Berlin-Siemensstadt, Germany, assignor to Sinfra A. G., St. Gallen, Switzerland, a Swiss corporation

Application December 23, 1933, Serial No. 703,732
In Germany December 23, 1932

5 Claims. (Cl. 66—139)

My invention relates to a knitting machine for the manufacture of tubular yarns, particularly of fancy yarns. Such fancy yarns are made of individual threads of different colors by knitting more or less long loops. In this manner a knitted thread results which alternately presents long loops of different colors so that such a thread makes the impression as if it were composed of individual pieces of thread of different color. It has hitherto only been possible to manufacture such threads by using particular cam rings for operating the knitting needles which have several high and low points, the number of high points corresponding to the number of alternations in color.

According to the present invention this effect may be attained in a simpler manner by moving during the knitting operation the thread guides towards or away from the knitting needles. The individual thread guides which guide threads of different colors are so operated one after the other that the threads are alternately supplied in a predetermined manner to the knitting needles in accordance with the shape of the cam rings for the thread guides. In this manner only one thread at a time is supplied to the knitting needles, whereas the other threads do not come within the operating range of the knitting needles.

30 My invention relates to the particular type of knitted strand elements, generally tubular in character, with interlocked loops, such as are disclosed in the U. S. Patents to Franz Meiwald Nos. 1,947,302, 2,006,275 and 2,016,870 in which also 35 the type of knitting head and needle bed is disclosed for which the present invention is particularly employed, and on which it is an improvement.

The thread guides may be designed to operate 40 in their own bed in the same manner as the knitting needles operate in their needle bed, and may be actuated by cam rings, cams or the like. They may be divided into two or more groups and be operated in groups. Two thread guides 45 or any greater number of thread guides may be operated in this manner. The cam rings may be concentrically arranged within one another, in order to obtain a short length of the thread guide head. This is of particular advantage, if 50 more than two cam rings are employed for operating the thread guides. The outer cam ring is preferably designed as support for the inner cam ring. Furthermore, it is necessary for the adjustment of the thread guides with relation 55 to the needles and to one another to arrange

the guide cylinder on the thread guide holder in such a manner that the guides become adjustable in the axial direction as well as peripherally. The thread guide head which contains the cam rings is rotated by means of a gear associated 5 with said head, the gear being driven from any convenient point of the machine. In such an arrangement the thread guide holder is stationary. In machines with revolving bobbins the thread guides must also rotate together with the 10 latter. Also the thread guide head casing and the thread guide holders may be caused to rotate in the same or the opposite direction, i. e., at the same speed as the knitting needles or at a different speed. By varying the speed various 15 effects may be obtained since this variation in speed changes the sequence of the threads supplied to a needle.

In the accompanying drawing an embodiment of my invention is illustrated in diagrammatic 20 form.

Fig. 1 represents an elevation, partly in section of the thread guide head and an elevational view of the needle cylinder, and

Fig. 2 shows a development of the cam rings 25 for operating the thread guide bars.

At the outset it may be stated that the thread guide mechanism shown in the upper portion of Fig. 1 and forming the subject matter of the present invention is mounted in the machine 30 frame (not shown) in vertical axial alignment with the knitting head 20, which latter is shown only in its general outline and in part, and which may be of the construction disclosed in the aforementioned patents, for producing a tubular knitting, also shown and described in said 35 patents, and in particular a knitting with interlocked loops which does not unravel. It is moreover assumed in the present example that the needle bed in head 20 rotates.

40 Further, while in Fig. 1 only two needles are shown, this does not mean that the device is limited to two needles and also to two thread guides 6, 6^a, the needle grooves 23 in needle bed 21—which rotates in this particular case—indicating that many more than two needles are provided for, depending upon the diameter of the knitting to be produced. Two needles and two thread guides only are shown for clearness sake and they are meant to be representative at the 45 same time of a plurality of groups of guides and needles. It is also assumed that there are as many stitch cams or knitting points arranged in the device as there are thread guides in a group.

With this understanding in mind, the construction is as follows:

1 denotes the thread guide holder which may be secured in any suitable portion of the machine frame (not shown). It carries a cylinder 2 for the thread guide bars 4, which carry the thread guides 6, 6^a at their lower ends as shown. The cylinder 2 has axially directed openings at its lower end, through which the thread guide bars 4 pass to the outside. 3 is a conical nut which is threaded onto the upper end of the cylinder 2 also conically threaded and which is besides radially split in a number of places as shown at 3^a, so that the cylinder is firmly locked 5 against the thread guide holder 1 when the split elastic upper parts of the cylinder 2 are clamped against it by nut 3. After loosening the nut, it is thus possible to adjust the entire thread guide head in the axial direction and, consequently, 10 all thread guides vertically with relation to the needles, so that when a guide tip 6 is in its lowermost position as shown in full lines, its guided thread 24 is within operative reach of a needle 22 which may then be in uppermost position as shown, and when a guide 6^a is in its uppermost position as shown in dotted lines, its guided thread 25 is out of reach of a needle 22, when the latter is in its uppermost position in 15 which it can engage a thread on its descent. 20 At the same time the thread guide head may be adjusted circumferentially about the axis of the thread guide holder 1 so that all thread guides may be adjusted at the periphery in relation to the incidental operating positions of the needles. 25 5 denotes a ball bearing which serves to support the head casing 11 on cylinder 2. The head casing 11 carries the cam rings consisting of the parts 7 to 10. The outer cam ring 9 carries the inner, circumferentially divided cam ring consisting of the parts 7 and 8 which by their complementary contours form the cam groove of that ring as shown in Fig. 2. The thread guides are divided into two groups I and II, and as mentioned at the beginning, for clearness' sake 40 only two guides 6 are shown as representative for guide group I, and two guides 6^a, representative for group II. It is quite obvious to any skilled person without further illustration, that as many thread guides and their bars may be provided 45 in the guide head as are required and as can operatively be accommodated on its circumference. The guide bars 4 of group I are provided with heels 8^a moving in the groove of the lower cam ring and the bars of the other group II are 50 provided with heels 9^a moving in the groove of the upper cam ring. In Fig. 1 the guide bars of the two groups appear behind one another and only the heel 9^a representative of group II is 55 visible. The head casing 11 is associated with a spur gear 12 which is keyed to casing 11, and which cooperates with the spur wheel 13. The gear 12 has great axial length in order that the gear 13 may cooperate with the gear 12 within a wide range of axially adjusted positions of the 60 thread guide head previously described without it being necessary to adjust the gear 12 upon head 11. The thread guide head casing may be driven through gear 13 by the main drive of the knitting machine in any of the many well-known 65 manners, and this obvious detail has therefore been omitted in the drawing.

In case the individual parts of the thread guide head should be separately driven, i. e. if both the thread guide head casing and the cylinder 2 70 should be driven, the thread guide head is then

provided with two drives which may be designed in the same manner as the drives for the needle cylinder, in cases where it is desired to have the needle cylinder also rotate besides the cam rings, and as is clearly shown in the Meiwald Patent 5 No. 2,016,870 above referred to. Since the drives for the above purpose may be of the type shown and described in aforesaid patent, the detail description and illustration thereof is not deemed necessary in the present case. 10

I claim as my invention:

1. In a knitting machine for knitting threads or tubular strands with interlocked loops in combination a knitting head having a needle bed with needles operating in the direction of the bed axis, and a thread guide head coaxially mounted with said needle bed and containing a plurality of thread guides, likewise movable in the direction of said bed axis and a plurality of cam cylinders engaging said guides and being 15 suitably operated in relation to the operation of the needles for operating said thread guides toward and away from the needles, to move the threads controlled by the guides into and out of engageable position with said needles, said 20 thread guides being divided into a plurality of groups, each of said groups being operatively connected to the cam surfaces of one of said cam cylinders.

2. In a knitting machine for knitting threads 30 or tubular strands with interlocked loops in combination a knitting head having a needle bed with needles operating in the direction of the bed axis, and a thread guide head coaxially mounted with said needle bed and containing a 35 plurality of thread guides, likewise movable in the direction of said bed axis and a plurality of cam cylinders engaging said guides and being suitably operated in relation to the operation of the needles for operating said thread guides toward 40 and away from the needles, to move the threads controlled by the guides into and out of engageable position with said needles, said thread guides being divided into a plurality of groups, each of 45 said groups being operatively connected to the cam surfaces of one of said cam cylinders, said cam cylinders being disposed one within the other, the outer cylinder serving as a support for the inner cylinder.

3. In a knitting machine for knitting threads 50 or tubular strands with interlocked loops in combination a knitting head having a needle bed with needles operating in the direction of the bed axis, and a thread guide head coaxially mounted with said needle bed and containing a 55 plurality of thread guides, likewise movable in the direction of said bed axis and a plurality of cam cylinders engaging said guides and being suitably operated in relation to the operation of the needles for operating said thread guides toward 60 and away from the needles, to move the threads controlled by the guides into and out of engageable position with said needles, said thread guides being divided into a plurality of groups, each of 65 said groups being operatively connected to the cam surfaces of one of said cam cylinders, the cam surfaces of said cam cylinders being arranged one above the other in the direction of the needle bed axis.

4. In a knitting machine for knitting threads 70 or tubular strands with interlocked loops in combination a knitting head having a needle bed with needles operating in the direction of the bed axis, and a thread guide head coaxially mounted with said needle bed and containing a 75

- plurality of thread guides, likewise movable in the direction of said bed axis and a plurality of cam cylinders one disposed within the other and engaging said guides, means for operating said cylinders in a suitable direction and at suitable speed with relation to the operation of said needles for operating said thread guides toward and away from the needles to move the threads controlled by the guides into and out of engageable position with said needles, said thread guides being divided into a plurality of groups, each group being operatively connected to the cam surface of one of said cam cylinders, said cam cylinders being disposed one within the other, the outer cylinder serving as a support for the inner cylinder.
5. In a knitting machine for knitting threads or tubular strands with interlocked loops in combination a knitting head having a needle bed with
- needles operating in the direction of the bed axis, and a thread guide head coaxially mounted with said needle bed and containing a plurality of thread guides, likewise movable in the direction of said bed axis and at least one cam suitably operated in relation to the operation of the needles for operating said thread guides toward and away from the needles, to move the threads controlled by the guides into and out of engageable position with said needles, said thread guide 10 head being composed of a guide cylinder serving as a guide for the thread guides, a head casing surrounding and journalled on said cylinder and containing said thread guide cam, means for producing relative rotation between said casing and 15 said cylinder, and means for centrally supporting said guide cylinder.

WILHELM NEININGER.
